UNITED STATES PATENT OFFICE.

LYMAN R. BLAKE, OF BROOKLYN, NEW YORK.

MECHANISM FOR LASTING BOOTS AND SHOES.

SPECIFICATION forming part of Letters Patent No. 241,524, dated May 17, 1881.

Application filed March 11, 1881. (No model.)

To all whom it may concern:

Be it known that I, LYMAN R. BLAKE, of Brooklyn, county of Kings, and State of New York, have invented an Improvement in Mechanism for Lasting Boots and Shoes, of which the following description, in connection with the accompanying drawings, is a specification.

This invention relates to mechanism for lasting boots and shoes, and is an improvement on that class of machines in which the edge of the upper, above and around the edge of the inner sole, is seized and held by gripping devices until drawn positively over upon the inner sole, where it is held until secured to the inner sole by means of a nail or tack driven automatically by a suitable driver.

This my machine is an improvement on United States Patent No. 183,919, to which reference may be had, wherein a single-moving device clamps the upper against the face of a fixed nose. In this my invention I intend to perform in an automatic manner substantially the same operation as that performed by a workman when lasting boots and shoes by hand.

My improved organized machine for lasting contains the following instrumentalities—viz., a horizontally-movable gripping device to seize the edge of the upper and draw or pull it over the inner sole toward the center of the last, the said gripping device being composed of two movable members; a raceway for comb-nails, pegs, or tacks; a separator to insure the delivery of the nails singly from the said raceway; and a driver to drive the said nails or tacks into the upper and inner sole while on the last.

As herein shown, one part of the gripping device to seize and draw the edge of the upper over upon the inner sole is provided with a nose having a nail-receiving opening, which, as the upper is laid over upon the inner sole, comes into position in line with the driver, driver-passage, and nail-tube, so that the driver in its descent strikes the comb-nail strip and detaches a nail from it, or strikes the head of the nail to be driven, and drives it from the nail-tube and the passage in the nose forming part of the gripping device, into the upper and inner sole.

That in which my invention particularly consists is hereinafter more fully set forth in the claims appended to this specification.

Figure 1 represents, in front elevation, a sufficient portion of the working part of a lasting machine to illustrate this my present invention. Fig. 2 is a vertical section of Fig. 1 on the line *xx*. Fig. 3 is a partial vertical section thereof, to illustrate the shoe-feeding device which directly engages the shoe, and mechanism for operating the said feeding device. Fig. 4 represents details of the cam and lever for operating that member of the gripping or pulling mechanism which acts as a nose, against which the work is held while the nail is being driven by the driver. Fig. 5, in a like manner, represents details of the lever and cam for moving that member of the gripping or pulling mechanism which is provided with the foot. Fig. 6 is a partial side view of the raceway and nail-tube. Fig. 7 is an interior view and partial section of one end of the raceway and nail-tube. Fig. 8 is a section of Fig. 7 on the line *yy*. Fig. 9 is a section of Fig. 7 in the line *zz*. Fig. 10 is a detail showing the gripping or pulling mechanism in its most forward position—the position it will occupy when grasping and holding the edge of the upper, as therein shown, between the nose and foot and over the inner sole on the last—the said figure showing the driver as having descended through the nail-receiving opening of the nose of the gripping or pulling device; and Fig. 11 is a cross-section of the comb-nail strip on an enlarged scale.

In the drawings, A is supposed to represent a suitable column having at its top a plate, B, upon which are mounted standards C, having proper boxes to receive the main rotating shaft D, it having a fly-wheel, D', connected with and operated by a link, D'', joined with the end of a suitable foot-lever or treadle. This shaft D' has a cam, E, provided with a cam-shaped flange to operate upon the roller or other stud *e* at the upper end of an arm, *e'*, of a rock-shaft, *e''*, the lower end of which, as at *e'*, has jointed with it the feeding device *e*⁵, the said cam and rock-shaft imparting to the feeding device, provided at its lower front end with a point or rough surface to engage the leather of the boot or shoe, a positive movement in the direction of the arrow thereon, a strong spring, *e*⁶, (see Fig. 3,) surrounding the rock-shaft *e''*, and bearing at one end upon the arm *e'*, moving the said feed in the opposite direction to feed the shoe forward. This feed device *e*⁵ is

provided with a slot, e^7 , which receives a pin at the lower end of a slide-bar, e^8 , fitted in a suitable groove or way made in the frame-work A^2 . This slide-bar e^8 is lifted by a spring, e^9 , (see Fig. 3,) which removes the forward end of the feed device e^5 from contact with the shoe to be fed forward, the said bar being actuated to force the acting end or point of the feed device against the material of the shoe by means of a lever, e^{10} , pivoted at e^{12} and operated by the cam E^2 , such devices constituting a four-motioned feeding mechanism.

In order to insure uniformity of distance between the nails or tacks driven in the upper, 15 the operator need only press the shoe being fastened upward firmly against the feed, and the latter, as it vibrates, will move the shoe horizontally over just the distance traveled by the lower end of the feeding device. In the patented machine referred to the operator was obliged to move the shoe horizontally under the nose, and in doing so moved it for a greater or less distance, and it was very difficult to insure regularity or uniformity in the distance between the tacks or nails driven into the shoe. 25

The driver-bar f , provided at its lower end with the driver f' , has at its top a lug, f^2 , connected by link f^3 with a vibrating lever, f^4 , pivoted at f^5 .

30 The rear end of the lever f^4 has a roller, pin, or stud, f^6 , which is operated upon by a cam, F , to raise the driver preparatory to its being thrown down quickly by means of the strong spiral or other spring f^7 .

35 The lower end of the driver, when the driver-bar is in its most elevated position, is held in the nail-tube 2, (see Fig. 2,) which serves as a guide for it. This nail-tube is open at its side to receive a nail or tack from the raceway a , 40 the lower end of which opens into the nail-tube, as represented in Figs. 6 and 7.

The comb-nails a^2 , or it may be tacks, are contained in the curved raceway a , as represented in Figs. 8, 9, the flanged head-forming 45 part 12 of the said comb-nail strip entering the groove 13 at one side of the said raceway.

The comb-nail strip is prevented moving backward by means of a spring-detent, 14, the forward end of which springs in between the 50 nails of the comb-nail strip, and the said strip is moved forward at the proper times to project its endmost nail into the nail-tube 2 under the driver f' by a pawl, 15, connected loosely with a lever, 17, pivoted at 18.

55 The lever 17 has a toe, 19, which is acted upon by a cam, 20, on the driver-bar f , to move the lever 17 and its pawl 15 and nail-strip forward, the said pawl moving for more or less of its stroke along over or in contact with the 60 adjustable detent, according to the length of effective stroke desired for the said pawl.

The pawl is kept pressed toward the raceway by a spring, 16, and the lever 17 is drawn backward by the spring 21.

65 That nail at the end of the comb-strip engaged by the pawl is placed in the passage a'

of the nail-tube 2, where it is supported by reason of its connection with the flanged part of the strip until the driver descends and strikes that part of the said flange which forms the 70 head of that nail then to be severed from the comb-strip and driven. As the driver descends it co-operates with the separator or strip-support a^3 , to be hereinafter described, and severs the endmost nail from the comb-strip and drives 75 it through the passage a' and through the passage g^3 , (the nose g^2 then being thrown forward, as in Fig. 10, in line with the driver,) and into the upper and inner sole. The said separator or strip-support a^3 is connected with 80 the upper portion of the nose-part g^2 of the horizontally-reciprocating griper member g . When the nail-driver is about to descend this separator a^3 covers the end of the raceway, and extends between the endmost nail and the next 85 one at the rear of it, so that the separator also acts as a support for the flange 12 of the comb-strip when it is struck by the driver, the support and driver cutting off the nail to be driven preparatory to being driven by the further descent of the driver.

The gripping or pulling mechanism is composed, essentially, of the two horizontally-reciprocating members g g' . (Shown fully in Fig. 2 in longitudinal section.)

95 The member g has a nose, g^2 , at the front end of its shank, which nose is provided with a nail-receiving opening, g^3 , that, when the said member is moved fully forward, as represented in Fig. 10, is brought into line with the passage a' of the nail-tube 2, to thus permit the nail presented in the nail-tube 2 to be driven by the driver through the passage g^3 into the upper and inner sole, the driver descending to the position shown in Fig. 10, after which it is 100 elevated by the cam F .

The upper end of the nose g^2 enters a slot made in the forward end of the bar g' of the pulling mechanism, and at its top has connected with it by a pin, 5, the separator or support a^3 . 105

The member g has at its rear end a pin, 6, which is engaged by a notched part of the lower end of the forked arm g^4 of a rocking lever pivoted at g^5 , the upper end, g^6 , of the said lever being provided with a suitable roll or stud to 115 permit the cam G to vibrate the said lever and reciprocate the member g longitudinally.

The member g' of the gripping or pulley mechanism is provided at its forward end with a rough-surfaced foot, g^7 , (see Figs. 2 and 10,) to 120 strike against the inner face of the upper above the inner sole and impinge or push the outer face of the upper against the beveled surface 8 of the nose or block g^2 , thus securely gripping and holding the edge of the upper, or upper 125 and lining, between them while the upper is being pulled or drawn over the last and inner sole toward the center of the last and nailed in place.

The member g' has its rear end connected with a spiral spring, g^8 , joined to the bolt 23, which acts to move the foot g^7 backward in the 130

direction of the arrow when not positively held forward by its operating-lever g^{10} .

After a nail has been driven into the upper the member g is moved backward into the position Fig. 2, the member g' following it.

When the parts are in the position Fig. 3 the edge of the upper, extended above the inner sole (the inner sole and upper being placed on a last held by hand or by a jack in any usual way) is inserted between the nose g^2 and above the foot g^7 , and the nose g^2 is then moved forward to grasp the said edge firmly between the end of the foot and the lower beveled part, 8, of the nose, after which the foot and nose are moved forward in unison.

If the last is held at its heel and toe by hand, the last will be moved backward to increase the strain upon the upper, and just as the foot and nose arrive fully forward the driver will descend and drive a nail.

The member g' and foot are moved by means of a lever, g^{10} , which acts upon shoulders g^{12} of the said member g' . (See Fig. 5.) This lever g^{10} is a rocking lever having its fulcrum at g^5 and a suitable roll or stud at its upper end to be acted upon by the cam G^2 , the latter vibrating the lever at the proper times.

The backward movement of the foot g^7 is determined by the adjustable stop h , it permitting the said foot to adapt itself to the thickness of the upper being lasted.

Should I employ headed tacks instead of comb-nails, the pawl 16 and detent 14 would be dispensed with, the device a^3 then acting solely as a separator to close the open end of the raceway while a nail is being driven, but when the said separator is withdrawn a nail at the end of the raceway will enter the nail-tube, and its point will be sustained by the shelf 40 25, the separator then lying between it and the next nail in the raceway.

As the nose is moved forward the passage g^3 will arrive under the nail, and the latter will drop into it, to be driven out by the driver.

45 By moving the pullers longitudinally, as described, and forcing the last in the opposite direction by hand, instead of holding the shoe or boot on a jack, as in United States Patent No. 135,540, tighter lasting may be done than in 50 the machine of the class shown in that patent.

The feeding device engages the upper and inner sole to feed the shoe forward while the parts are in the position shown in Figs. 6 and 3.

I claim—

1. In a lasting-machine, horizontally-movable gripping or pulling devices composed of two independent members, $g g'$, one being made as a foot to bear against the inner side of the edge of the upper, and the other as a perforated block or nose to bear against the outer surface of the edge of the upper, the foot impinging the upper against the said block and pinching or holding it firmly between them while the independent members of the said gripping or pulling devices are moved forward in unison to pull or draw the edge of the upper over upon the inner sole.

2. The gripping devices to grasp the edges of the upper, and a raceway for the nails to be driven into the upper and inner sole, combined with a separator located at the lower end of the raceway, substantially as described.

3. The gripping devices to grasp the edges of the upper and hold the same, and a tube, raceway, and separator for the nails, combined with a driver to drive a nail, substantially as described.

4. In a lasting-machine, the gripping devices to grasp and pull the upper over the inner sole, and a driver to drive a nail into the upper and inner sole while held by the grippers, moved forward under the driver, combined with a feeding device to engage the material of the shoe and feed it forward, substantially as described.

5. The vibrating arm e^3 and its connected feeding device e^6 , combined with the reciprocation slide-bar e^8 , to raise and lower the said feeding device, substantially as described.

6. The nail-driver and driver-bar, lever 17, toe 19, and pawl 15, combined with the raceway and adjustable detainer 14, substantially as described.

In testimony whereof I have signed name to this specification in the presence of two subscribing witnesses.

LYMAN R. BLAKE.
